CLAIM

The ornamental design for a battery charger pedestal as shown and described.

DESCRIPTION

FIG. 1 is a front, left perspective view of a battery charger pedestal, according to an embodiment;

FIG. 2 is a front, right perspective view of the battery charger pedestal of FIG. 1;

FIG. 3 is a front elevation view of the battery charger pedestal of FIG. 1;

FIG. 4 is a rear elevation view of the battery charger pedestal of FIG. 1;

FIG. 5 is a left side elevation view of the battery charger pedestal of FIG. 1;

FIG. 6 is a right side elevation view of the battery charger pedestal of FIG. 1;

FIG. 7 is a top plan view of the battery charger pedestal of FIG. 1; and,

FIG. 8 is a bottom plan view of the battery charger pedestal of FIG. 1.

The ornamental design which is claimed is shown in solid line. The broken lines of equal length dashes in the drawings are for the purpose of illustrating portions of the battery charger pedestal and form no part of the claimed design. Broken lines formed by unequal length dashes (i.e., dash-dot) define bounds of the claimed design.
